FIRING RATE REDUCER

Clarence E. Simpson, Springfield, Mass.

Application January 23, 1943, Serial No. 473,299

15 Claims. (Cl. 89—27)

(Granted under the act of March 3, 1883, as amended April 30, 1928; 370 O. G. 757)

The invention described herein may be manufactured and used by or for the Government for governmental purposes, without the payment to me of any royalty thereon.

This invention relates to automatic firearms, particularly to a firing rate reducing mechanism for such automatic firearms.

The firing rate of any particular automatic weapon can be said to be largely determined by the mass of the moving breech parts, the length of movement thereof, the energy absorption characteristics of any buffer provided to stop such movement of the breech parts and, of course, the amount of energy imparted to the moving breech parts by the discharge of a cartridge. These determining factors are relatively independent of any particular method of securing automatic operation, whether the firearm be of the gas operated, blowback or recoil type. It will be noted that none of these determining factors is capable of convenient adjustment to thereby effect a variation in the firing rate. Furthermore, the stringent weight requirements set up for modern military automatic firearms tend to produce a very high firing rate. This high firing rate is generally much above the firing rate which would permit extended or continuous firing of the automatic weapon, due not only to excessive heating of the barrel of the firearm, but also the effect of the rapid firing upon accuracy of the weapon. This latter disadvantage is particularly apparent in automatic shoulder weapons in which there is a considerable tendency of the muzzle end of the barrel to raise upward or "climb" during automatic firing. Since many military situations require extended automatic firing it is essential that the firing rate of an automatic firearm be capable of substantial reduction so as to permit extended automatic firing without excessive heating and still not sacrifice any of the other desirable characteristics of the weapon.

Firing rate reducing mechanisms have heretofore been devised for such purpose but such prior designs have accomplished firing rate reduction only at the expense of sacrificing other desirable military characteristics of the particular firearm, such as elimination of semi-automatic firing, substantial increase in weight or a weakening of the stock by firing rate reducing mechanisms inserted therein.

Accordingly it is an object of this invention to produce an improved firing rate reducing mechanism for firearms of the automatic type.

It is a further object of this invention to produce a firing rate reducing mechanism which 55

does not affect the semi-automatic firing properties of the automatic firearm.

Another object of this invention is to provide a firing rate reducing mechanism which may be entirely contained within a trigger guard group of the firearm and which does not substantially increase the weight of such firearm.

It is a particular object of this invention to accomplish firing rate reduction of an automatic firearm by a method involving three distinct stops of the moving bolt parts during the breech opening and closing part of the operation cycle of the automatic firearm.

The specific nature of the invention as well as other objects and advantages thereof will clearly appear from a description of a preferred embodiment as shown in the accompanying drawing in which:

Fig. 1 is a longitudinal sectional view of a trigger guard showing the arrangement of the firing rate reducing mechanism and related sear release mechanism. Also shown in longitudinal section is a breech member with sear in engagement with a sear notch in the breech member.

Fig. 2 is a partial perspective view of the top portion of the trigger guard shown in Fig. 1.

Fig. 3 is a perspective view of the carrier.

Fig. 4 is a perspective view of the sear spring.

Fig. 5 is a front elevational view of the change lever.

Fig. 6 is a cross sectional view of the change lever taken along the plane 6—6 of Fig. 5.

Fig. 7 is a cross sectional view of the change lever taken along the plane 7—7 of Fig. 5.

Fig. 8 is a side elevational view of the connector with the web of the carrier shown in engagement therewith.

Fig. 9 is a perspective view of the depresser pin.

Fig. 10 is a fragmentary longitudinal sectional view showing an alternative modification of the firing rate reducing mechanism shown in Fig. 1.

Fig. 11 is a top elevational view of a spring utilized in the construction shown in Fig. 10.

The three-stop method of securing firing rate reduction is illustrated in two preferred embodiments which will be described in detail. The method can also be described generally, independent of any particular firearm construction except that the existence of a reciprocating

50 breech member in the automatic firearm shall be assumed. Upon discharge of the cartridge from such firearm, the breech member is unlocked and moves rapidly to the rear under the influence of a force derived in any desired manner from the discharge of the cartridge. The

first stop of such reciprocating breech member is caused by the breech member striking a buffer or otherwise reaching the end of its rearward movement in the usual manner. Under the influence of the buffer recoil force and the compressed operating spring, the breech member then reverses its direction and starts forward to its battery position. In accordance with this invention, at some point in this forward movement of the breech member, the breech member engages a sear and is brought to the second stop by the sear. The sear is mounted for limited reciprocal movement in a plane parallel to the axis of the breech member and a strong spring opposes any forward movement of the sear and hence is compressed by the force exerted on the sear when the breech member strikes the sear and is stopped thereby. This sear spring is sufficiently strong to move both the sear and the breech member engaged therewith rearwardly against the bias of the operating spring. Near the end of this limited rearward movement the sear is tripped out of engagement with the breech member. The breech member is then under the sole influence of the operating spring which stops the rearward movement of the breech member, making the third stop, and then drives the breech member forward to its battery position. The extraction and ejection of the discharged cartridge is accomplished on the initial rearward movement of the breech member by a conventional mechanism while the loading of the next cartridge may be conventionally accomplished either on the initial or final forward movement of the breech member. This three-stop method naturally results in a reduction in the firing rate of the automatic weapon due to the delay inherent in the repeated stopping and reversing of the movement of the reciprocating breech member.

From the preceding general description of the three-stop method of securing firing rate reduction, it is apparent that the method is independent of any particular type of automatic firearm construction so long as a reciprocating breech member is included. Therefore the following description of two preferred embodiments of this invention as applied to an automatic firearm of the type disclosed in U. S. Patent No. 1,293,022 to John M. Browning should not be construed as limiting the scope of this invention to that particular type of firearm.

In Fig. 1 there is shown in assembled relation, a portion of the elements of an automatic firearm generally of the type disclosed in U. S. Patent No. 1,293,022 to John M. Browning. The portion shown comprises a trigger guard frame 1 which is provided with a pistol grip portion 1p. This trigger guard frame is supported by the receiver and stock of the firearm (not shown) in its conventional relation therewith and underlies a breech member 2 which is conventionally mounted in the receiver for sliding reciprocal movement therein.

The top of the trigger guard frame 1 is provided with two sets of vertical extensions 1a and 1b on each side of the frame 1 defining a channel 1c between such extensions. A long rectangularly-shaped carrier member 3 is mounted for limited reciprocal movement within the channel 1c. The rear end of the carrier 3 is bifurcated in two portions 3a and 3b. The central portion 3h of the carrier 3 is hollow except for a transverse member 3c which extends across the hollow

portion 3h for a purpose that will be described later. At the forward end of the hollow portion 3h the walls of the carrier 3 have opposed slots 3d and 3e formed in the walls. The extreme forward portion of the carrier 3 defines a cylindrical open chamber 3f. When the carrier member 3 is mounted within the channel 1c the chamber 3f acts as a spring seat for a spring 4. The other end of the spring 4 is supported by a spring seat 1n provided in the trigger frame and a guide pin 5 is secured to the base of the spring seat 1n and projects into the turns of the spring 4.

In the forward opposed frame extensions 1b holes 1e are provided in which a pin 6 is inserted, the pin 6 also traversing the slots 3d and 3e of the carrier 3. The rear opposed frame extensions 1a are slotted as shown at 1d and a pin 7 passes through these slots and engages the holes 3p and 3r in the carrier 3. Thus reciprocal movement of the carrier 3 within the channel 1c is limited by the length of the slots 1d, 3d and 3e.

A T-shaped sear 8 is provided. This sear closely resembles the conventional sear but is provided with a greatly increased length of depending foot portion 8a. In the central portion of the sear a hole 8e is provided and the sear is secured to the trigger guard assembly by the engagement of the hole 8e by the pin 7, the foot portion of the sear projecting down between the portions 3a and 3b of the carrier 3. Limited pivotal movement of the sear about the pin 7 is therefore permitted without interference with the carrier 3. The rear end of the sear 8 is provided with a contact surface 8b which when the sear is pivoted slightly counterclockwise as viewed in Fig. 1 projects into the path of a correspondingly shaped latching surface 2c of the breech member 2 and thereby locks the breech member 2 against any further forward movement of the breech member. The latching surface 2c is the rear wall of a recess 2a in the bottom of the breech member.

Pivotal movement of the sear 8 is accomplished by a trigger arrangement very similar to that disclosed in U. S. Patent No. 1,293,022 to John M. Browning. The trigger 9 is provided with a forwardly extending portion 9a in which is located the trigger pivot hole 9b. The trigger is secured in position in the trigger frame by engagement of the hole 9b by the pin 6. The forwardly extending portion 9a of the trigger fits into the hollow portion 3h of the carrier 3, entering that portion which is forward of the transverse member 3c. Immediately above the finger engaging portion of the trigger 9, there is a bifurcated trigger extension 9c and projecting across the central portion of the bifurcated extension 9c is a pin 9d suitably secured in each of the bifurcated portions. A connector 10 of conventional shape is supported by the pin 9d engaging a suitably shaped recess 10a in the base of the connector.

The actual direction of movement of the connector 10 when the trigger 9 is pulled is controlled by a conventional change lever 11. The change lever 11 essentially comprise a transverse pin mounted in the trigger guard frame 1 and provided on its exterior ends with an operating handle 11a. The change lever 11 is arranged to lie in the path of an arcuate surface 10c of the connector 10 when the connector is raised by operation of the trigger. The change lever 11 may be rotated to three distinct positions and in each position a different type of camming action is exerted on the arcuate surface 10c of the connector 10. In place of the flat leaf spring

usually provided to yieldingly hold the change lever 11 in any of its three positions, a detent 12 is provided for this purpose. The detent 12 comprises a relatively long partly hollow cylindrical portion 12a which is loosely fitted in a vertical hole 1g provided in the trigger guard frame 1. The detent arm 12b is secured to the top of the cylindrical portion 12a and at right angles thereto and projects over the change lever 11. This detent arm 12b is provided with a depending tooth 12c which may engage any one of three adjacent teeth 11c provided on the change lever 11. The detent 12 is resiliently biased into engagement with the teeth 11c by the force of a spring 13 which is mounted within the hollow portion of the detent 12 and compressed therein by a pin 14 also mounted within the same hollow portion and on top of the spring 13. The spring 13 is compressed by engagement of the top of the pin 14 with a transverse web portion 3j provided in the carrier 3. Hence the change lever 11 is resiliently held in position, as shown in Fig. 1, but may be forcibly rotated in a clockwise direction into two additional positions, the teeth 11c acting to cam the detent 12 upwardly to permit the rotation. Further rotational movement of the change lever 11 beyond the three positions defined by the teeth 11c is prevented by suitable stops on the change lever which are not shown. In the position of the change lever 11 shown in Fig. 1, a recess 11d in the body of the lever is positioned directly above the arcuate surface 10c of the connector 10. Hence in this position of the change lever 11, actuation of the trigger 9 will move the connector 10 directly upward without any interference being exerted by the change lever 11 as the arcuate surface 10c enters the recess 11d. By such movement the top surface 10b of the connector 10 is brought into engagement with the bottom surface of the forward end of the sear 8 and thus the sear 8 is pivoted slightly clockwise to effect the release of the breech member 2.

It should be mentioned that a conventional flat spring 15 is provided to bias the sear into its cocked position. One end 15a of the spring 15 is secured within the carrier 3 by being inserted in opposed grooves 3g provided in the side walls at the end of carrier 3. The other end of spring 15 comprises a three-pronged fork portion, the two exterior fingers 15b are parallel while the central forked portion 15c projects slightly below the surface of the other two forks. The two forks 15b engage the top surface of the front end of the sear 8 exerting a force thereon which biases the sear in a counterclockwise direction. The central finger 15c engages a sloped surface 10e on the top of the connector 10 and thereby exerts a constant bias on the connector 10 tending to pivot it in a clockwise direction on the pin 9d.

Clockwise pivotal movement of the connector 10 is prevented by engagement of a rear vertical surface 10f provided on the top of the connector 10 with the forward end of the web 3j of the carrier 3. The connector 10 is supported on its front side by a small projection 3m integrally formed on the inner wall of the carrier 3. This projection engages a shoulder 10g on the adjacent side of connector 10. Immediately adjacent to and below the vertical surface 10f there is provided a sloped cam surface 10h on the connector 10. Upon actuation of the trigger this surface engages a correspondingly shaped undersurface 3k of the web 3j and the camming action between such surfaces

made to pivot the connector 10 counterclockwise and moves the top of the connector forward against the bias of the middle finger 15c of the spring fork. The connector 10 is guided in this movement by the projection 3m against which the shoulder 10g of the connector slidably bears. This movement of the connector 10 is of sufficient extent to move the top sear engaging surface 10b of the connector out from under the forward end of the sear 8 and hence permits the sear to snap back to its normal position under the bias of the spring fork fingers 15b. This produces semi-automatic firing of the firearm as actuation of the trigger first releases the sear from cocked engagement with the breech member and then returns the sear to its breech member engaging or cocked position. Thus the trigger must be released and pulled again to fire the next round. When the change lever 11 is rotated clockwise to its next position, a projecting small shoulder 11e along the base of the walls defining the recess 11d of the change lever 11 is thereby rotated in the proximity of the end of the arcuate surface 10c of connector 10. In this position the actuation of the trigger 9 will again raise the connector 10 and the arcuate surface 10c enters into the recess 11d of change lever 11; however, the interaction of the cam surface 10h and the corresponding surface 3k on the web 3j will not produce a movement of the connector 10 out of engagement with the sear 8 for the end of arcuate surface 10c now strikes the shoulder 11e preventing further movement of the connector 10. Therefore in this position of the change lever the sear 8 remains pivoted and disengaged from the breech member as long as the trigger is pulled and hence this condition produces automatic operation of the firearm.

Rotation of change lever 11 to its third and final position brings a solid portion of the change lever into the path of the arcuate surface 10c of the connector 10 and therefore stops the upward movement of the connector 10 due to actuation of the trigger before the connector can move a sufficient distance to rotate the sear out of latched engagement with the breech member. Hence this position of change lever 11 constitutes the safety position of the firearm.

A recess 1r is provided in the trigger frame 1 immediately below the pin 7 and the foot 8a of the sear extends into this recess. This foot 8a has a projecting heel 8c on the forward end of its base, the heel projecting a substantial distance beyond the remainder of the base 8d of the sear foot 8a. In the bottom of the recess 1r, a hole 1h is provided into which a bolt-like plunger member 16 is inserted. This plunger 16 is resiliently biased upward by a spring 17 in the bottom of the hole 1h. The top of the plunger 16 normally abuts against the base of the heel 8c of the sear foot 8a. A depressor pin 18 is mounted within the trigger frame 1 to latch the plunger 16 out of engagement with the heel 8c. The member 18 comprises a transverse pin extending through the trigger frame 1 and provided on its exposed extremity with an interior socket head 18c so that it might be rotated by insertion of a suitable tool or the nose of a bullet. A flange 18b is provided in the center of the depressor pin 18 and this flange serves to secure the depressor latch in its proper position in the trigger frame 1 when the wooden side pieces 19 are fastened to each side of the pistol grip 1p of the trigger frame as by the screws 19a. A portion of the depressor 18 projects into the hole 1h in which the plunger 16

is located. A clearance cut 16a is provided in the plunger 16 to accommodate the projecting portion of the depressor 18. A clearance cut 18a is provided in the depressor 18. This cut 18a permits the plunger 16 to move freely in the hole 1h, when the depressor is in the position shown in Fig. 1. If however the depressor pin 18 is rotated 90° clockwise from the position shown in Fig. 1, then a solid portion of the depressor pin will extend into the hole 1h, entering the recess 16a in the plunger 16. Further rotation of the depressor pin 18 will engage the base of the clearance cut 18a with the base of the clearance cut 16a of the plunger 16 and force the plunger 16 downward and hence out of engagement with the heel 8c of the sear foot 8a. The friction exerted upon the flange 18b of the depressor pin by the wooden side pieces 19 will be sufficient to maintain this position and hence the plunger 16 is effectively latched out of engagement with the sear 8 whenever the depressor pin 18 is rotated clockwise.

The transverse member 3c extending across the hollow portion of the carrier 3 has already been mentioned. A horizontal rearward projection 9e is provided in the top of the trigger 9. The position of this projection is such that in the inactuated position of the trigger the projection 9e lies directly in the path of frontal movement of the transverse member 3c and hence frontal movement of the carrier is prevented. However when the trigger is actuated, the projection 9e is raised above the transverse member 3c and the transverse member can move freely within a recess 9f directly below the projection 9e in the trigger 9. Thus no limitation is placed on the movement of the carrier 3 when the trigger 9 is maintained in its actuated position.

Before proceeding with the description of the various modes of operation of this improved construction, it is desired to emphasize again that any conventional bolt action and methods of extraction, ejection, and feeding of cartridges may be utilized so long as there is provided a reciprocating breech member which may be engaged by the sear 8 and firing of the weapon thus prevented until the sear 8 is released from engagement therewith.

Full automatic operation without rate reduction

Despite the several changes in construction as evident from the foregoing description, the operation of this improved mechanism under full automatic fire without rate reduction is essentially the same as the operation of the firearm disclosed in U. S. Patent No. 1,293,022 to John M. Browning. The change lever 11 is set in its central position. Assuming that a cartridge is in the magazine of a firearm and the breech member 2 has been retracted to its cocked position wherein the sear 8 engages the latching surface 2c of the breech member, the actuation of the trigger 9 raises the connector 10 in substantially a vertical path, hence raising the front end of the sear 8 and tripping the rear end of the sear out of engagement with the breech member. The breech member therefore drives forward under the force of the compressed operating spring (not shown) picking up the cartridge from the magazine and loading and firing the cartridge in the conventional manner. A force from the resulting explosion is applied to the breech member driving it rapidly rearward. Since the shoulder 11e in the recess 11d of the change lever 11 is abutting against the end of the arcuate surface

10c of the connector 10, counterclockwise pivotal movement of the connector due to camming action of surfaces 10h and 3k is prevented and hence the connector 10 remains in engagement with the front end of the sear 8. Therefore as long as the trigger is maintained in the pulled position, the rear end of the sear 8 remains out of the path of the breech member 2 and the weapon continues to fire automatically at its natural rate since the breech member 2 reciprocates freely without delay of any sort being introduced.

Semi-automatic without rate reduction

It is likewise possible to secure normal semi-automatic operation with the construction described. To obtain this type of operation, the change lever 11 is rotated counterclockwise to its extreme position. The depressor pin 18 is rotated clockwise to latch the plunger 16 out of engagement with the sear foot 8a. Then after retraction and cocking of the breech member 2, the actuation of the trigger 9 raises the connector 10 in a vertical path hence tripping the sear 8 out of engagement with the breech member 2. However, the connector 10 is pivoted counterclockwise by the co-action of its surface 10h with the web surface 3k and moved out of engagement with the front end of the sear 8. Hence the sear 8 immediately returns to the cocked position due to the bias of the spring fingers 15b. On the recoil stroke of the breech member 2 following the discharge of the cartridge, the bottom breech member surface 2b rides over the rear end of the sear 8. The sear is entirely free to pivot counterclockwise a slight amount against the bias of the spring forks 15b to permit the passage of breech member 2. As soon as the recess 2a in the breech member 2 becomes adjacent to the rear end of the sear 8, the sear pivots back to its cocked position under the influence of its spring forks 15b and thus latches the breech member against forward movement under the influence of the compressed operating spring. Regardless of whether the trigger has been maintained pulled or released, it is therefore necessary to actuate the trigger again to effect the discharge of the second cartridge.

Full automatic fire at full reduced rate

To secure reduced rate, full automatic fire, the change lever 11 is left in the same position as utilized in securing normal rate semi-automatic fire. The depressor pin 18 however is rotated counterclockwise to release the plunger 16 and permit it to resiliently engage the heel 8c of the sear foot 8a under the influence of the spring 17. With the components set as described and, as usual, assuming that the magazine is loaded with cartridges and that the breech member 2 has been manually retracted to its cocked position with sear surface 8b in engagement with breech member latching surface 2c, the weapon may be fired automatically at a reduced rate by pulling the trigger and the connector 10 in this instance is exactly the same as already described in the semi-automatic operation, i. e., the connector 10 raises the front end of the sear 8 hence tripping the rear end of the sear out of engagement with the breech member 2 and permitting the breech member to drive forward to load and fire the cartridge. The connector 10 at the same time is cammed out of engagement with the front end of the sear 8 permitting the sear to return to the cocked position under the influence of spring finger 15b. The connector 10 remains in this position, independent of the sear 8, so long as the

mal automatic and semi-automatic fire is identical to that described for the previous modification with the only exception being that instead of operating the depressor pin to secure semi-automatic operation, it is necessary in this modification to fasten down spring portion 20b by means of the screw 21 in the manner described.

To secure automatic operation with reduced firing rate, the screw 21 is turned to release spring portion 20b. The spring portion 20b thus yieldingly engages the bottom of the heel 32 of the sear foot 31. Then upon pulling the trigger 9 and holding the trigger pulled, the same cycle of operations as described in the previous modification occurs, namely, the sear pivots, unlatching the breech member and permitting the breech member to drive forward to load and fire the cartridge. At the same time the connector 10 moves out from under the sear 30 permitting the sear to return to its cocked position under the influence of spring forks 15b. The breech member flies back on its recoil movement overriding the rear end of sear 30, strikes a buffer and starts forward under the influence of the compressed operating spring when it is stopped by engagement with the rear end of the sear 30. The impact of the breech member 2 upon the sear 30 is transmitted through the pin 7 to the carrier 3. The carrier moves forward compressing the spring 4 until the carrier is stopped by engagement of its forward end with its spring seat 1f. The forward movement of the carrier of course moves the sear 30 forward and the heel 32 moves forward over the end of the spring portion 20b and that spring portion now engages the sloped base 33 of the sear foot 31. The compressed carrier spring then moves the carrier 3, the sear 30, and the breech member 2 latched therewith rearward against the force of the compressed operating spring, thus producing the second stop and reversal of movement of the breech member 2. Such rearward movement brings the rear end of the heel 32 into engagement with the forward end of the spring portion 20b. This engagement results in a counterclockwise pivoting of the sear 30. Such pivoting drops the rear end of the sear 30 out of engagement with the breech member 2. The breech member 2 is thus under the sole influence of the compressed operating spring which stops and reverses its rearward movement and drives it forward to load and fire the next cartridge. Hence the third stop and reversal of direction of the breech member 2 is accomplished. The completion of the rearward movement of the carrier 3 drags the heel 32 of the sear foot 31 up over the end of the spring portion 20b, permitting the sear 30 to return to its cocked position under the influence of spring forks 15b. The elements are thus restored to their initial position ready for another cycle of automatic firing.

The second described modification of course utilizes the same three-stop principle as does the first modification. It is particularly recommended wherever the requirements of the particular weapon do not permit the use of a pistol grip and where there is no requirement that the means for changing from full automatic fire to reduced rate automatic fire and vice versa shall be readily available without disassembly of the weapon.

I claim:

1. In an automatic firearm having a receiver and a reciprocating breech member, a sear arranged to engage the breech member on its forward stroke, means mounting said sear to said receiver permitting limited linear movement of

the sear with respect to the receiver; resilient means arranged to be stressed by forward linear movement of the sear under impact of the breech member engagement and means engageable by said sear on rearward movement thereof under the bias of said resilient means for disengaging said sear from said breech member.

2. In an automatic firearm having a receiver and a reciprocating breech member, a sear arranged to pivot into engagement with the breech member on its forward stroke, a spring biasing said sear into a breech member engaging position, means mounting said sear to said receiver permitting limited linear movement of the sear with respect to the receiver; resilient means arranged to be stressed by forward linear movement of the sear under impact of the breech member engagement and means engageable by said sear on rearward movement thereof under the bias of said resilient means for disengaging said sear from said breech member.

3. In an automatic firearm having a receiver and a reciprocating breech member, a sear arranged to pivot into engagement with the breech member on its forward stroke, a spring biasing said sear into a breech member engaging position, means mounting said sear to said receiver permitting limited linear movement of the sear with respect to the receiver; resilient means arranged to be stressed by forward linear movement of the sear under impact of the breech member engagement, an extension on said sear and a spring biased member arranged to be engaged by said sear extension to pivot said sear out of breech member engagement by the rearward movement of the sear under the bias of said resilient means.

4. In an automatic firearm having a receiver and a reciprocating breech member, a sear arranged to engage the breech member on its forward stroke, means mounting said sear to said receiver permitting limited linear movement of the sear with respect to the receiver; resilient means arranged to be stressed by forward linear movement of the sear under impact of the breech member engagement, means engageable by said sear on rearward movement thereof under the bias of said resilient means for disengaging said sear from said breech member, and manually operated means arranged to render said preceding means inoperative.

5. In an automatic firearm having a receiver and a reciprocating breech member, a sear arranged to pivot into engagement with the breech member on its forward stroke, a spring biasing said sear into a breech member engaging position, means mounting said sear to said receiver permitting limited linear movement of the sear with respect to the receiver; resilient means arranged to be stressed by forward linear movement of the sear under impact of the breech member engagement, an extension on said sear, a spring biased member arranged to be engaged by said sear extension to pivot said sear out of breech member engagement by the rearward movement of the sear under the bias of said resilient means and manually operated means arranged to render said spring biased member inoperative.

6. In an automatic firearm having a receiver and a reciprocating breech member, a sear carrier mounted on said receiver for limited linear movement, a spring arranged to be stressed by forward movement of said carrier with respect to the receiver, a sear pivotally mounted on said carrier and arranged to engage the breech mem-

trigger is maintained in the pulled position. On the recoil stroke of the breech member 2, the rear end of the sear 8 is depressed by the bottom surface 2b of the breech member 2 and then under the influence of the spring fingers 15b the sear 8 pivots its rear end into the recess 2a where the sear surface 8b engages the latching surface 2c of the breech member as the breech member begins its return movement. It should be understood that any desired buffering mechanism can be used to stop and reverse the recoil movement of the breech member. Such buffer stop constitutes the first stop and reversal of direction of the breech member. The second stop of the breech member is brought about as described by the breech member 2 striking the sear 8. The force of this impact is transmitted through the sear 8 and the pin 1 to the carrier 3 and the carrier starts to move forward under such impact. The forward movement of the carrier compresses the carrier spring 4 and is stopped by engagement of the frontal end of the carrier 3 with the spring seat 1n. This movement is sufficient to slide the heel 8c of the sear foot 8a off the top of the plunger 16 and the plunger 16 of course rises under the influence of spring 17 to a higher position where it engages the base portion 8d of the sear foot 8a. As already mentioned the carrier spring is quite strong and in fact sufficiently strong to move the carrier, sear and breech member 2 latched thereto, rearward against the force of the compressed operating spring. Thus a second reversal in the motion of the breech member 2 is obtained. Such rearward movement brings the rear side of the heel 8c of the sear foot 8a in to engagement with the front edge of the plunger 16. Due to a slight inclination of the base 8d of the sear foot 8a, this contact initiates a clockwise pivoting of the sear 8. One effect of this pivotal movement of the sear 8 is that the rear end of the sear is dropped out of engagement with the breech member 2 leaving the breech member under the influence of only the compressed operating spring which effects the third stop of the breech member and the third reversal of movement, driving the breech member forward to load and discharge the next cartridge. The other effect of the pivotal movement is that the plunger 16 is depressed by the toe of the sear foot 8a to such an extent that the heel 8c rides up over the front end of the plunger 16 as the carrier 3 completes its rearward movement. Thus the sear 8 is free to return to its cocked position under the influence of spring fingers 15b. Hence all elements of the mechanism are returned to their initial positions in the cycle and hence automatic firing at the reduced rate will continue so long as the trigger is depressed. It is obvious that the firing rate is substantially reduced due to the time consumed in the stopping and reversing of the breech member 2 brought about by the described construction.

The automatic firing at the reduced rate may be halted by release of the trigger. Such release drops the trigger projection 9e into the path of the transverse member 3c and hence stops the forward movement of the carrier 3 when the breech member first strikes the end of the sear 8. It is apparent that during the automatic firing at the reduced rate the transverse member 3c reciprocates without interference in the recess 9f with in the trigger 9.

Thus the described construction produces automatic firing at a substantially reduced rate merely by a simple external adjustment of the change lever 1f and the depressor pin 18. The amount

of weight added to the firearm by the elements producing the rate reduction is practically negligible. At the same time full automatic operation at the normal firing rate as well as normal semi-automatic operation can be obtained.

In Fig. 10 there is shown an alternative modification of a rate reducing mechanism utilizing the same three-stop principle applied in the previously described modification. In this modification wherein like numerals indicate parts similar to the modification already described, there is no necessity for the addition of a pistol grip to the trigger guard frame. There is shown a trigger guard frame 1 of the same construction as that described in U. S. Patent No. 1,293,022 to John M. Browning. The carrier 3, the carrier spring 4, the trigger 9, the connector 10, the change lever 11, and the transverse member 3c are all of the same construction and have the same relationship with each other as the modification already described. Only the detent, sear and the means for releasing the sear during reduced rate automatic firing are modified. In place of the spring biased detent 12 utilized in the previous modification for latching the change lever 11 in one of its three positions, there is provided a flat spring member 20.

This spring 20 lies in a correspondingly shaped recess 1j in the base of the channel 1c in the rear end of the top of the trigger frame. A hole 20a in the rear end of the spring 20 is engaged by a small vertical pin 1k provided in the base of the channel 1c to secure the spring 20 against movement within the recess 1j. The spring 20 comprises two integrally formed elements 20b and 20c. The spring portion 20b is formed as a single leaf out of the central portion of the spring 20 while the spring portion 20c is formed from the two sides of the spring metal remaining after the punching out of the central portion 20b. The end of spring portion 20c extends above the change lever 11 and is suitably shaped to resiliently engage the teeth 11c of the change lever 11. The spring portion 20b extends forwardly and at a slight upward angle to the base of the channel 1c.

The central section of spring portion 20b is provided with a longitudinal slot 20d. A threaded hole 1m is provided in the base of the recess 1j underlying the slot 20d in spring portion 20b. A screw 21 is threaded into hole 1m. This screw 21 has a long narrow head which when aligned with the slot 20d will pass through the slot. Thus by depressing spring portion 20b and permitting head 21a of the screw 21 to project through the slot 20d, the spring portion 20b can be securely held down parallel to the base of the channel 1c by turning the screw 21 to a position where the head 21a is at right angles to the axis of the slot 20d. The sear 30 utilized in this modification is in general similar to the sear already described in the previous modification with the exception however that the sear foot 31 is greatly reduced in length. This of course is necessary since this modification does not utilize a recess beneath the sear such as provided in the pistol grip portion 1p of trigger frame 1 of Fig. 1. This sear 30 however has forward and rear ends shaped identically to the sear of Fig. 1 which cooperate with the connector 10 and the breech member latch surface 2c respectively in the same manner as in the previous modification. The sear foot 31 also has the same projecting heel 32 and sloped base 33.

The operation of this modification under nor-

ber on its forward stroke thereby moving said sear carrier forwardly, a spring pivotally biasing the sear into its breech member engaging position and means engageable by said sear on the rearward movement of said sear carrier under the bias of said first mentioned spring for disengaging said sear from the breech member.

7. In an automatic firearm having a receiver and a reciprocating breech member, a sear arranged to engage the breech member on its forward stroke, means mounting said sear to said receiver permitting limited linear movement of the sear with respect to the receiver; resilient means arranged to be stressed by forward linear movement of the sear under impact of the breech member engagement, means disengaging said sear from the breech member by the rearward movement of said sear under the bias of said resilient means, trigger means effective to initially release the sear from the breech member and a stop actuated by release of said trigger means to engage said sear mounting means to limit the forward linear movement of said sear.

8. In an automatic firearm having a receiver and a reciprocating breech member, a sear arranged to pivot into engagement with the breech member on its forward stroke, a spring biasing said sear into a breech member engaging position, means mounting said sear to said receiver permitting limited linear movement of the sear with respect to the receiver; resilient means arranged to be stressed by forward linear movement of the sear under impact of the breech member engagement, an extension on said sear, a spring biased member arranged to be engaged by said sear extension to pivot said sear out of breech member engagement by the rearward movement of the sear under the bias of said resilient means, trigger means effective to initially release the sear from the breech member and a stop actuated by release of said trigger means to engage said sear mounting means to limit forward linear movement of said sear.

9. In an automatic firearm having a receiver and a reciprocating breech member, a sear arranged to engage the breech member on its forward stroke, means mounting said sear to said receiver permitting limited linear movement of the sear with respect to the receiver; resilient means arranged to be stressed by forward linear movement of the sear under impact of the breech member engagement, means disengaging said sear from the breech member by the rearward movement of said sear under the bias of said resilient means, manually operated means arranged to render said preceding means inoperative, trigger means effective to initially release the sear from the breech member and a stop actuated by release of said trigger means to engage said sear mounting means to limit forward linear movement of said sear.

10. In an automatic firearm having a receiver and a reciprocating breech member, a sear arranged to pivot into engagement with the breech member on its forward stroke, a spring biasing said sear into a breech member engaging position, means mounting said sear to said receiver permitting limited linear movement of the sear with respect to the receiver; resilient means arranged to be stressed by forward linear movement of the sear under impact of the breech member engagement, an extension on said sear, a spring biased member arranged to be engaged by said sear extension to pivot said sear out of breech member engagement by the rearward movement

5 of the sear under the bias of said resilient means, manually operated means arranged to render said spring biased member inoperative, trigger means effective to initially release the sear from the breech member and a stop actuated by release of said trigger means to engage said sear mounting means to limit forward linear movement of said sear.

11. In an automatic firearm having a receiver and a reciprocating breech member, a sear carrier mounted on said receiver for limited linear movement, a spring arranged to be stressed by forward movement of said carrier with respect to the receiver, a sear pivotally mounted on said carrier and arranged to engage the breech member on its forward stroke thereby moving said sear carrier forwardly, a spring pivotally biasing the sear into its breech member engaging position, means operative by the rearward return movement of said sear carrier under the bias of said first mentioned spring after the impact of breech member engagement to disengage said sear from the breech member, trigger means effective to initially release the sear from the breech member, and a stop secured to said trigger means, said stop arranged to engage said sear carrier in the released position of said trigger means to limit forward movement of said carrier.

12. In an automatic firearm having a receiver and a reciprocating breech member, a sear carrier mounted on said receiver for limited forward movement, a spring arranged to be stressed by forward movement of said carrier with respect to the receiver, a sear having its central portion pivotally secured to said carrier, the rear end of said sear arranged to engage the breech member on its forward stroke, a spring pivotally biasing the sear into its breech member engaging position, semi-automatic trigger means engageable with the forward end of said sear to initially release the sear from the breech member, a depending sear portion, and a latch resiliently engaging said depending sear portion and effective during rearward movement of said sear and sear carrier under the bias of said first mentioned spring to pivot said sear out of breech member engagement.

13. In an automatic firearm having a receiver and a reciprocating breech member, a sear carrier mounted on said receiver for limited forward movement, a spring arranged to be stressed by forward movement of said carrier with respect to the receiver, a sear having its central portion pivotally secured to said carrier, the rear end of said sear arranged to engage the breech member on its forward stroke, a spring pivotally biasing the sear into its breech member engaging position, semi-automatic trigger means engageable with the forward end of said sear to initially release the sear from the breech member, a depending sear portion, a latch resiliently engaging said depending sear portion and effective during rearward movement of said sear and sear carrier under the bias of said first mentioned spring to pivot said sear out of breech member engagement and manually operated means arranged to hold said latch out of engagement with said depending sear portion.

14. In an automatic firearm having a receiver and a reciprocating breech member, a sear carrier mounted on said receiver for limited linear movement, a spring arranged to be stressed by forward movement of said carrier with respect to the receiver, a sear having its central portion pivotally secured to said carrier, the rear end

of said sear arranged to engage the breech member on its forward stroke, a spring pivotally biasing the sear into its breech member engaging position, semi-automatic trigger means engageable with the forward end of said sear to initially release the sear from the breech member, a depending sear portion, a latch resiliently engaging said depending sear portion and effective during rearward movement of said sear and sear carrier under the bias of said first mentioned spring to pivot said sear out of breech member engagement, and a stop secured to said trigger means and effective in the released position of said trigger means to limit forward movement of said sear carrier.

15. In an automatic firearm having a receiver and a reciprocating breech member, a sear carrier mounted on said receiver for limited linear movement, a spring arranged to be stressed by forward movement of said carrier with respect to

the receiver, a sear having its central portion pivotally secured to said carrier, the rear end of said sear arranged to engage the breech member on its forward stroke, a spring pivotally biasing the sear into its breech member engaging position, semi-automatic trigger means engageable with the forward end of said sear to initially release the sear from the breech member, a depending sear portion, a latch resiliently engaging said depending sear portion and effective during rearward movement of said sear and sear carrier under the bias of said first mentioned spring to pivot said sear out of breech member engagement, a stop secured to said trigger means and effective in the released position of said trigger means to limit forward movement of said sear carrier and manually operated means arranged to hold said latch out of engagement with said depending sear portion.

CLARENCE E. SIMPSON.
